DESIGN FOR A HAT

Ruby Wedd, Richmond Hill, N. Y.

Application November 28, 1942, Serial No. 108,902

Term of patent 3½ years

To all whom it may concern:

Be it known that I, Ruby Wedd, a citizen of the United States of America, residing in Richmond Hill, county of Queens and State of New York, have invented a new, original, and ornamental Design for a Hat, of which the following is a specification, reference being had to the accompanying drawing, forming part thereof.

Fig. 1 is a front perspective view of a hat showing my new design, the hat being in tilted position.

Fig. 2 is a rear view of Fig. 1, and

Fig. 3 is a top plan view of the hat shown in Fig. 1, in normal position.

I claim:

The ornamental design for a hat, substantially as shown.

RUBY WEDD.
